The ornamental design for a saliva collector, as shown and described.

DESCRIPTION

FIG. 1 is a perspective view of the saliva collector;

FIG. 2 is a bottom perspective view thereof;

FIG. 3 is a front view thereof;

FIG. 4 is a back view thereof;

FIG. 5 is a first side view thereof;

FIG. 6 is a second side view thereof; and,

FIG. 7 is a top view thereof; and,

FIG. 8 is a bottom view thereof.

The broken lines in FIG. 7 are included for the purpose of illustrating a portion of the saliva collector that forms no part of the claimed design.
